D. F. WHATMORE
SHOE

Des. 120,901

Filed Oct. 19, 1939

FIG. 1.

FIG. 2.

Inventor.
Delia F. Whatmore.

UNITED STATES PATENT OFFICE

120,901

DESIGN FOR A SHOE

Delia F. Whatmore, Seattle, Wash.

Application October 19, 1939, Serial No. 87,740

Term of patent 14 years

To all whom it may concern:

Be it known that I, Delia F. Whatmore, a citizen of the United States, residing at Seattle, in the county of King and State of Washington, have invented a new, original, and ornamental Design for a Shoe, of which the following is a specification, reference being had to the accompanying drawing, forming part thereof.

Figure 1 is a perspective view of the shoe showing my new design.

Figure 2 is a plan view with the shoe open showing the tongue sewed on both sides.

My design of a woman's shoe as illustrated, is characterized by a plain vamp in combination with an upper portion, which, when closed as in Figure 1, gradually lessens in circumference upwardly so as to form a snugly fitting top substantially of a conical frustum shape, said uppers having goring inserts on each side thereof as shown.

I claim:

The ornamental design for a shoe, substantially as shown and described.

DELIA F. WHATMORE.
